UNITED STATES PATENT OFFICE.

WARREN M. OSBORN, OF CHICAGO, ILLINOIS.

RAIL-TIE PLATE.

Application filed October 26, 1925. Serial No. 64,802.

My invention relates to tie plates for railroad rails, and its object is to provide a new and improved device of this character which when used in the ordinary manner of tie-plates between a rail and tie provides a two-way anti-creeper which connects the rail-base to the plate to transmit to the plate and its tie the longitudinal movements or thrusts of the rail in both directions caused by the wave movement of the rail under traffic or by the expansion and contraction of the rail, while permitting up and down movement or play of the rail on the plate.

In the accompanying drawings, Fig. 1 is a top plan view of a tie-plate constructed in accordance with my invention; Fig. 2 is a sectional view of the plate on the line 2—2 in Fig. 1 with the lower portion of a rail in cross-section and a clip in side elevation; Fig. 3 is a fragmentary view partly in top plan and partly in section taken on the line 3—3 in Fig. 2 looking in the direction of the arrows; Fig. 4 is a detail view similar to Fig. 3 but showing the clip in its initial position to be seated in the plate; Fig. 5 is a view similar to Fig. 2 with a tie in side elevation and the clip provided with a depending wing; Fig. 6 is a fragmentary view similar to Fig. 3 and taken on the line 6—6 in Fig. 5 looking in the direction of the arrows; and Fig. 7 is a detail rear view of the clip shown in Figs. 5 and 6.

In the drawings the reference letter A designates the base of a rail, B its web broken away to omit its head for simplicity of illustration, and D is one of the cross-ties to which the plate is spiked in any suitable manner.

The tie-plate consists of a flat metallic body 1 which is provided near one edge with a rail-abutting shoulder 2 and with spike-holes 3 to receive the spikes which engage the underlying tie to hold the plate on the tie and the rail on the plate. The rail is connected to the plate by an anchor clip which grips the rail-base and is seated in a seat in the plate provided with a resilient gate which allows the clip to be passed through it to enter its seat and clamp the rail and then closes to retain the clip in place on the rail and in its seat. The plate is provided in one or both of its ends with a longitudinal slit 4 which extends from near its center through one end of the plate and divides that end of the plate into sections

which can be temporarily spread apart to pass the clip into its seat and then closed to lock the clip in position. The slit is preferably near one side of the plate and is laterally enlarged near its outer end where the edge 60 of the rail-base overlies it to form a rectangular seat 5, and the outer ends of its walls are laterally beveled or flared to form a bell-mouth 6. The clip or stay 7 is of spring metal and comprises upper and lower 65 jaws 8 and 9, respectively, which have a normal separation slightly greater than the thickness of the edge of the associated rail-base so that the clip may be easily started on the base and when it is driven to its final 70 position on the upwardly beveled base it will clamp the latter with a strong grip. The lower jaw is of sufficient size to snugly fill a seat in the plate, and its sides 75 preferably are beveled inwardly toward its vertical central line to provide a wedge-shaped toe 10.

In the form shown in Figs. 5, 6 and 7 the tie-plate is of sufficient size to provide a suitable seating surface for the rail-base and 80 to have one of its sides extend beyond the side of the tie D, as shown for example in Figs. 5 and 6, when the plate is spiked thereto in track. The extended or overhanging side of the tie-plate is provided near its edge 85 with a slit 4 and a seat 5 of the same construction as above described, and the clip is provided with a depending wing 11 on its lower jaw to abut against the side of the tie 90 to transmit longitudinal thrusts of the rail in one direction directly against the tie.

The dimensions of the parts are such that when a plate is assembled under a rail-base the edges of the latter overlie the clip-seats with one edge bearing against the shoulder 95 2 as shown in Figs. 2 and 5, and the parts thus assembled are spiked to the tie. A clip is then positioned with its toe in a bell-mouth 6, and its lower jaw 9 is driven through the gate 12 formed by the outer 100 portion of the slit 4 in the margin of the plate until it enters the associated seat 5; the passage of the clip through the gate causes the sections of the plate to spread apart as shown in Fig. 4, and after the clip 105 enters its seat the gate is closed and the outer walls of the seat retain the clip in place on the edge of the rail-base as shown in Figs. 2 and 5. As the clip is narrow, being only about five-eighths (5/8) of an inch wide 110

in practice, it avoids distortion of the metal of the plate when the parts are being assembled; and as the height of the lower jaw may be proportioned to the thickness of the associated plate without necessitating any adzing of the ties, the clips will not rise out of their seats under the vertical action of the rails due to their wave-like motion from passing traffic. As the seat in the tie-plate is spread apart laterally when the anchor-clip is moved into position therein the dimensions of the seat and clip can be such that when the parts are assembled the sides of the seat will fit snugly against the side walls of the clip to enable the clip to abut against the tie-plate in either direction of the rail without lost motion or play; this effective engagement of the anchoring parts results from the mode of their assemblage which is made possible by the slit plate. The anchor-clip grips the rail and bears against the sides of the seat in the tie-plate, so that all longitudinal movements or thrusts which the rail may have in either direction are taken by the tie-plate, and as the tie-plate is spiked to the tie the resistance of the latter embedded in the ballast is utilized against the longitudinal movements of the rails in both directions. By this organization a rail-anchorage is provided which resists rail-creeping in both directions while permitting vertical movement of the rails on the plates.

While I prefer to provide each plate with two seats as shown, it is obvious that only a single seat may be used or desired, in which case it will preferably be located at the shoulder-end of the plate as shown for example in Figs. 2 and 5. The seat may be of any convenient size and form, and the clip may be of any suitable construction to co-operate with the seat and act as a stay or anti-creeper for the rail. Tie plates have been made by various methods for many years of malleable iron, wrought iron and steel of various grades affording sufficient elasticity to permit them to be used in the manner and for the purposes above described; with some steels the sections will automatically close the gate behind the clip, but when other materials are used it may be necessary to do this by driving the sections together. In either case my invention may be realized with well-known commercial plates.

55 I claim:

1. A rail anchor comprising a tie-plate having a longitudinal slit extending through one end thereof, and a rail-fastener adapted to be driven into said slit into locking engagement with said plate and into engagement with a rail-base on the plate.

2. A rail anchor comprising a tie-plate having a longitudinal slit extending through one end thereof, and a resilient clip adapted to be driven into said slit into locking en-

gagement with said plate and into gripping engagement with a rail base on the plate.

3. A rail anchor comprising a tie-plate having a longitudinal slit extending through one end thereof and having an interior seat, and a resilient clip adapted to be driven into said slit into locking engagement with said seat and having opposite jaws in gripping engagement with a rail base on the plate.

4. A rail anchor consisting of a tie-plate having a longitudinal slit extending through one end and formed with a seat, and a rail-clip adapted to be driven into said slit and engaging said seat and a flange of a rail-base on the plate.

5. A rail anchor consisting of a tie-plate having a longitudinal slit located near one side thereof and extending through one end and formed with an enlarged seat, and a rail-clip adapted to be driven into said slit and fitting said seat and embracing a flange of a rail-base on the plate.

6. A rail anchor consisting of a tie-plate having a longitudinal slit located near one side thereof and extending through one end and formed with a lateral seat and a bell-mouth, and a rail-clip adapted to be driven into said slit and fitting said seat and embracing a flange of a rail-base on the plate.

7. A rail anchor consisting of a tie-plate having near one side a longitudinal slit extending through one end to provide a gate and formed with a normally closed seat, and a rail-fastener adapted to be driven through said gate and engaging said seat and a flange of a rail-base on the plate.

8. A rail anchor consisting of a tie-plate having near each side a longitudinal slit extending through one end to provide a gate and formed with a normally closed seat, and rail-fasteners adapted to be driven through said gates and engaging said seats and the opposite flanges of a rail-base on the plate.

9. A rail anchor consisting of a tie-plate having near each side a longitudinal slit extending through one end to provide a gate and formed with a normally closed seat, and resilient clips adapted to be driven through said seats into locking engagement with said seats and into engagement with the opposite flanges of a rail-base on the plate.

10. A rail anchor consisting of a tie-plate constructed with an extension projecting beyond one side of the associated tie and having a slit transverse to the length of a rail-base and extending through one end of the plate, a rail-stay adapted to be driven into the slit into locking engagement with the plate and into engagement with the base, and a wing on the stay projecting below the plate.

In testimony whereof I hereto affix my signature.

WARREN M. OSBORN.
